UNITED STATES PATENT OFFICE.

WILLIAM F. KOCH, OF CUSTER COUNTY, COLORADO.

BUCKLE.

1,115,549.

Specification of Letters Patent.

Patented Nov. 3, 1914.

Application filed November 11, 1913. Serial No. 800,378.

To all whom it may concern:

Be it known that I, WILLIAM F. KOCH, a citizen of the United States, residing in the county of Custer and State of Colorado, 5 have invented a certain new and useful Improvement in Buckles, of which the following is a full, clear, and exact description.

This invention is an improvement in buckles and, while of general applicability, it is 10 especially adapted for use on hame straps.

Hame strap buckles, being necessarily drawn very tight and being furthermore likely to become firmly set by the strains put upon them in use, are difficult to detach and 15 the object of my invention is the provision of means whereby the tongue will be positively and readily withdrawn from the strap without the necessity of pulling on the latter or manually releasing it.

20 In the single sheet of drawings accompanying this application and forming a part hereof Figure 1 is a perspective view of a hame strap provided with a buckle embodying my invention, the buckle being shown in 25 clasped position and the free end of the strap being raised to more clearly show all the parts; and Fig. 2 is a perspective view of the parts shown in Fig. 1, the buckle being detached.

30 Referring to the drawings, 3 indicates the strap to which my buckle has been attached by riveting or any suitable means.

40 4 indicates the frame of the buckle which, in the preferred form shown in the drawings, is provided with a pair of elongated eyes 5 in which is mounted the rectangular member 6 which carries the tongue 7. The tongue 7 is preferably freely mounted on the member 6 though it may be non-revolubly mounted thereon if desired. On the side of the member 6 opposite to that carrying the tongue there is attached a hand-hold 8, in this instance shown as a short strap. These parts are so shaped and proportioned that 45 the member 6 is free to slide within the limits imposed by the ends of the eyes and the length of the tongue is greater than the distance between the inner ends of the eyes 5 and the outer end 9 of the frame and less

than the distance between the outer ends of 50 the eyes and the end 9 of the frame.

Operation: When the device is to be buckled the member 6 is held at the inner ends of the eyes and the parts secured in the same manner as with an ordinary buckle, 55 the tongue 7 entering one of the holes 10 in the strap 3. The tension on the strap 3 will retain the tongue parallel with the frame and always in engagement with its outer end 9, and the greater the pull the more firmly 60 will the buckle be held in place. When it is desired to detach the parts a sharp, quick pull on the hand-hold 8 will readily withdraw the tongue from the hole in which it is in engagement and the strap will be released, 65 as shown in Fig. 2.

Having thus described my invention, what I claim and desire to secure by Letters Patent is:

1. In a device of the class described, a 70 frame having a pair of elongated eyes projecting therefrom at right angles to the plane of said frame, a tongue carrying member mounted to have a limited sliding movement in said eyes, a tongue upon said member adapted to engage that side of the frame from which said eyes project, and a hand-hold attached to said tongue carrying member. 75

2. In a device of the class described, a 80 frame having a pair of eyes projecting therefrom at right angles to the plane of said frame, a tongue carrying member mounted to have a limited sliding movement in said eyes, a tongue upon said member, the length of the tongue being greater than the distance between the inner ends of said eyes and the outer end of said frame but less than the distance between the outer ends of said eyes and the outer end of said 90 frame, and a hand-hold attached to said tongue carrying member. 85

3. In a device of the class described, a frame having a pair of elongated eyes projecting therefrom at right angles to the 95 plane of said frame, a substantially rectangular tongue carrying member having one of its sides mounted to have a limited slid-

ing movement in said eyes, a tongue mounted on the same side of said tongue carrying member and adapted to engage that side of the frame from which said eyes project, and a hand-hold attached to the opposite side of said tongue carrying member.

In testimony whereof, I have hereunto af-

fixed my signature in the presence of two witnesses.

WILLIAM F. KOCH.
